UNITED STATES PATENT OFFICE.

JAMES F. BAILEY, OF COLUMBIA, SOUTH CAROLINA.

COTTON TRAMPER OR PACKER.

Application filed May 13, 1921. Serial No. 469,182.

To all whom it may concern:

Be it known that I, JAMES F. BAILEY, a citizen of the United States, residing at Columbia, in the county of Richland and 5 State of South Carolina, have invented certain new and useful Improvements in a Cotton Tramper or Packer; and I do hereby declare the following to be a full, clear, and exact description of the invention, 10 such as will enable others skilled in the art to which it appertains to make and use the same.

The invention relates to tramping or packing machinery for compressing loose material into compact form for economizing 15 space and easy handling.

The invention relates more particularly to the driving mechanism for the plunger for equalizing the stresses and strains and 20 providing for a comparatively long stroke and a relatively small driver.

Other objects and advantages will be apparent and suggest themselves as the 25 nature of the invention is understood.

While the drawings illustrate an embodiment of the invention it is to be understood that in adapting the same to meet different conditions and requirements, various changes 30 in the form, proportion and minor details 35 of construction may be resorted to without departing from the nature of the invention.

Referring to the accompanying drawings forming a part of the specification,

Figure 1 is a side view of a machine 40 illustrative of the invention.

Figure 2 is a top plan view thereof.

Figure 3 is a detail longitudinal section on the line $x-x$ of Figure 2.

Figure 4 is a transverse section on the 45 line $y-y$ of Figure 2.

Corresponding and like parts are referred to in the following description and designated in the several views of the drawings by like reference characters.

The frame work for supporting the operating part may be of any construction and arrangement depending largely upon the design and nature of the machine. As 50 shown the frame work embodies uprights or posts 1, cross bars 2 and longitudinal bars 3 supported upon the cross bars 2. Cross pieces 4 are supported upon corresponding end portions of the longitudinal bars 3. A short longitudinal bar 5 is supported upon the cross pieces 4 at an intermediate point and receives a stub shaft 55

or axle 6 whose ends project beyond opposite sides of the bar 5 and receive gear wheels 7 loose thereon. A longitudinal shaft 8 is mounted in cross 60 pieces 9 supported upon the bars 3 opposite the end portion supporting the cross pieces 4. A pinion 10 fast to the inner end of the longitudinal shaft 8 is disposed between the gear wheels 7 and is in meshing engagement therewith. It will thus be understood that the gear wheels 7 are reversely driven when the machine is in operation. The style of teeth between the elements 7 and 10 is immaterial and may be of any preferred construction. A transverse shaft 11 is geared at its inner end to the outer end of the longitudinal shaft 8 and transmits motion thereto. As shown a beveled gear 12 secured to the outer end of the shaft 8 70 is in mesh with a bevel pinion 13 fast to the inner end of the shaft 11. Pulleys 14 and 15 are mounted upon the outer end of the transverse shaft 11. The pulley 14 being tight whereas the pulley 15 is loose. A 75 drive belt 16 cooperates with the pulleys 14 and 15 and is adapted to receive power from any suitable source. A rod 17 disposed transversely of the machine has one end in engagement with the drive 80 belt 16. An operating lever 18 is connected with the opposite end of the rod 17 and provides convenient means for operating the rod 17 to shift the drive belt 16 from one pulley to the other as may be required. 85

The plunger 19 is mounted to receive a reciprocating movement and is retained in place and guided in its movement by a guide 20 which preferably consists of a U-shaped frame having its side members 90 mounted in vertical sleeves 21 secured to the longitudinal bars 3. Pitmen 22 connect the plunger 19 with the gear wheels 7 in the two extreme vertical positions of the pitmen 22 they are in the same plane and 95 coincide with the plane of the guide 20 and when the plunger 19 is midway between its upper and lower movement the pitman 22 inclines in opposite direction. The relative angular disposition of the pitman 22 varies throughout the stroke of the plunger 19 and this is due to the reverse rotation of the gear wheels 7 to which the upper ends of the pitman 22 are connected. Said arrangement results in an equalization 100 of the load upon the power transmitting means. Moreover the pitman may be con- 105

nected to the gear wheels 7 beyond their gearing with the result that provision is had for an increased length of stroke of the plunger 19. As shown the pitmen 22
5 are connected to projections 23 of the gear wheels 7. These projections 23 may form a part of the gear wheels or may be applied thereto in any preferred way. It may be stated that the gear wheels 7 constitute
10 drivers and may be of any construction and have the pitmen 22 connected thereon in any way and at any distance from their axes.

Having thus described the invention, what I claim is:—

15 In a machine of the character specified,

a supporting member, a stub axle mounted upon said member and having its ends projecting beyond opposite sides thereof, drivers loosely mounted upon the projecting ends of the stub axle, a plunger, pitmen exterior 20 to the drivers and forming connecting means between them and the plunger and means for imparting reverse rotary movement to the drivers.

In testimony whereof I affix my signature in presence of two witnesses.

JAMES F. BAILEY.
